(57) **CLAIM**

The ornamental design for a paddle handle having oval-shaped exterior, as shown and described.

DESCRIPTION

FIG. 1 is a top view of a paddle handle having a oval-shaped exterior according to the present invention;

FIG. 2 is a front view of the handle design of FIG. 1;

FIG. 3 is bottom view of the handle design of FIG. 1;

FIG. 4 is a rear view of the handle design of FIG. 1;

FIG. 5 is a right side view of the handle design of FIG. 1; and,

FIG. 6 is a left side view of the handle design of FIG. 1. The broken lines are for illustrative purposes only and form no part of the claimed design.
